[57] **CLAIM**

The ornamental design for a twisted pendant for bag, clothing and trinket goods, as shown and described.

DESCRIPTION

FIG. 1 is a first side perspective of a twisted pendant for bag, clothing and trinket goods showing my new design.

FIG. 2 is a second perspective view from the opposite side thereof;

FIG. 3 is a plan view thereof from the side of the twisted face;

FIG. 4 is a plan view thereof from the side of the flat face;

FIG. 5 is a first side view thereof;

FIG. 6 is a second side view thereof, opposite to the view of FIG. 5;

FIG. 7 is a top side view thereof;

FIG. 8 is a bottom side view thereof.

FIG. 9 is a first side perspective view of a second variation of twisted pendant according to the design having a substantially rectangular shape and being twisted with respect to its longitudinal axis;

FIG. 10 is a second side perspective view from the opposite side thereof;

FIG. 11 is a plan view thereof, the opposite plan view being equal;

FIG. 12 is a side view thereof, the opposite side view being equal;

FIG. 13 is a top side view thereof; and,

FIG. 14 is a bottom side view thereof.
